(57) **CLAIM**

The ornamental design for a video camera, as shown and described.

DESCRIPTION

FIG. 1 is a top isometric view of a video camera with the attached cable in accordance with our new design;

FIG. 2 is a top isometric view thereof, the cable removed for ease of illustration;

FIG. 3 is a bottom isometric view of the video camera with the attached cable;

FIG. 4 is a bottom isometric view thereof, the cable removed for ease of illustration;

FIG. 5 is a right side isometric view of the video camera with the attached cable;

FIG. 6 is a right side isometric view thereof, the cable removed for ease of illustration;

FIG. 7 is a left side isometric view of the video camera with the attached cable;

FIG. 8 is a left side isometric view thereof, the cable removed for ease of illustration;

FIG. 9 is top perspective view thereof, the cable removed for ease of illustration;

FIG. 10 is a front elevation view thereof; and,

FIG. 11 is a rear elevation view thereof, the cable removed for ease of illustration.

The portions of the video camera shown in broken lines in FIGS. 1-3, 5 and 7-11 are included for illustrative purposes only and form no part of the claimed design.
